UNITED STATES PATENT OFFICE.

LEWIS MORTIMER SLOCUM, OF LOS ANGELES, CALIFORNIA.

MOVIE DOLL.

Application filed January 11, 1921. Serial No. 436,522.

To all whom it may concern:

Be it known that I, LEWIS MORTIMER SLOCUM, a citizen of the United States, residing at Los Angeles, in the county of Los Angeles and State of California, have invented new and useful Improvements in Movie Dolls, of which the following is a specification.

My invention relates generally to amusement and entertainment devices, and more particularly to a doll or manikin, the principal object of my invention being to provide a glove or mitten-like member of flexible material such as fabric, and which member is adapted to be positioned on the hand and fingers, which member is marked or decorated so as to represent clothing, and, further, to combine with said glove or mitten-like member an object shaped and 10 marked to represent a person's head, and the latter being provided with a recess that is adapted to receive one of the fingers of the operator's hand, and thus the clothes and head representing parts can be moved to 15 simulate the movements of a person's head and body.

Further objects of my invention are to produce a doll or manikin that is relatively simple in construction, capable of being 20 easily and cheaply produced, and, further, to provide a body in the nature of a doll or toy that will afford amusement and entertainment for children.

With the foregoing and other objects in view, my invention consists in certain novel features of construction and arrangement of parts that will be hereinafter more fully described and claimed and illustrated in the accompanying drawings in which—

40 Figure 1 is a front elevational view of a doll embodying my invention.

Figure 2 is a rear elevational view of the flexible body portion of the doll, and with the head thereof removed.

45 Figure 3 is a vertical section taken on the line 3—3 of Figure 2.

Figure 4 is a vertical section taken centrally through the head portion of the doll.

50 Figure 5 is a plan view of a disc that is utilized in the head portion of the doll for firmly retaining the same upon the finger of the operator.

The member that represents the body of the doll or manikin is preferably constructed of fabric or like flexible material, and it comprises an elongated substantially tu-

bular member that is composed of a front section 10, and a back section 11, the side edges of which are connected in any suitable manner, and formed integral with the upper 60 portions of said sections are laterally projecting hollow flexible members 12 that are adapted to receive the thumb and a finger on the hand of the manipulator, and which members are intended to represent the arms 65 of the doll or manikin.

Extending upwardly from the upper end of the tubular member formed by the sections 10 and 11, and centrally arranged between the members 12 is a flexible tubular 70 member 13, that is adapted to receive the index finger on the hand of the manipulator, and said member 13 with the finger therein, is adapted to serve as a support for the head 75 of the doll.

The outer face of section 10 of the body representing member may be printed, stenciled or decorated to represent feminine garments, and the outer surface of the rear section 11 may be printed, stenciled or decorated 80 to represent masculine garments. The head portion 14 of the doll may be formed of any suitable light weight material, such as papier-mâché, celluloid, or the like, and formed therein and extending upwardly 85 from the under side, is a recess 15 of sufficient size to receive the index finger of the manipulator.

Arranged in the lower portion of the head and lying across the opening therein, is a device 90 for retaining the head firmly on the index finger, said device being preferably in the form of a disc 16 of thin flexible material such as cardboard or celluloid, the same being provided with a centrally arranged 95 perforation 17, and having a series of radially disposed slots 18 that extend outwardly from said central opening. The edge of this disc is embedded in the lower portion of the head 14 so that the opening 17 is centrally 100 arranged within recess 15.

Obviously the head 14 may be shaped as desired, and marked or decorated so as to represent either a fanciful face or the features of some well known person. In the 105 manipulation of my improved doll or manikin, the hand is inserted in the open lower end of the flexible tubular body composed of the sections 10 and 11, and the index finger is positioned in the tubular extension 13 with 110 the thumb in one of the tubular extensions 12, and the second or third finger positioned

in the other tubular extension 12. The head of the doll or manikin is now arranged on top of the body, with the index finger and the tubular member 13, that encloses the 5 same, positioned within recess 15.

In thus applying the head, the sections of material in the disc 16 around the central opening 17 and between the radial slots 18, will bend upwardly, as illustrated by the 10 dotted lines in Figure 4, and thus press against the index finger to firmly retain the head in position thereupon.

After the parts of the doll or manikin are thus combined and mounted upon the hand 15 of the manipulator, the head, body and arms of the doll or manikin can be moved in simulation of the movements of the corresponding parts of a person, and, as a result, the moving doll or manikin will prove a considerable source of amusement and pleasure 20 for children.

Obviously minor changes in the size, form and construction of my improved doll or manikin may be made and substituted for 25 those herein shown and described, without departing from the spirit of my invention, the scope of which is set forth in the appended claims.

I claim as my invention:

30 1. A doll or manikin comprising a substantially tubular flexible member, the outer surfaces of which are marked or decorated to represent wearing apparel, one end of said tubular member being provided with a plurality of relatively small tubular extensions 35 adapted to receive the thumb and fingers of

a person's hand, a member shaped and marked to represent a person's head, and provided with an aperture that is adapted to receive one of the finger receiving members on the flexible tubular body, and a perforated slotted member within the aperture in said head for gripping the finger and the smaller tubular member that is inserted therein. 40

2. A doll or manikin comprising a substantially tubular body member formed of flexible material, the outer surface of which is marked or decorated to represent wearing apparel, said flexible body member having 50 relatively small tubular extensions that are adapted to receive the thumb and certain fingers of a person's hand, a member shaped and marked to represent a head, which member is recessed to receive one of the smaller 55 tubular members on the body member, and a series of radially disposed resilient members arranged within said recess for yieldably engaging the tubular member and the finger that are inserted therein. 60

3. In a doll or manikin, a head portion recessed to accommodate a finger, and a finger gripping member formed of flexible material and arranged in spanning relation to the recess, said member being formed with a central opening and split radially at intervals with the split portions communicating with the opening. 65

In testimony whereof I have signed my name to this specification.

L. MORTIMER SLOCUM.
